SOFA AND DOUBLE BED COMBINATION

Harry S. Vakassian, New York, N. Y.

Application July 18, 1951, Serial No. 237,378

6 Claims.

(Cl. 5—18)

1

My invention relates to that type of convertible furniture which can be used optionally as a sofa or as a double bed.

Objects of my invention are to provide a sofa and double bed combination which forms a rearwardly declining or sloping seat for several persons when used as a sofa an which can be converted into a bed having a horizontal surface of a size about twice as large as the sofa seat area, and to accomplish this conversion by extracting an additional bed frame from the sofa, tilting the sofa seat into a horizontal position and complementing the height of the extracted bed frame by a layer of cushions which, when the combination is used as sofa, form the back of the sofa.

Other objects are to provide the combination with a stationary base and with a mattress so positioned and supported over this base that the extractable bed frame can be placed between the base and the mattress in the sofa condition of the combination, and can be shifted to the front like a drawer, and to provide the bed frame with feet which can be folded into this frame when the frame is shifted under the mattress.

Further objects are to support the mattress in each of its two different positions firmly so that the mattress will hold the weight of the person or persons resting thereon, to support the mattress by the base in the bed condition and to support the mattress by the bed frame in the sofa condition.

Still other objects are to facilitate the conversion, to connect the mattress and the base by a releasable catch in the bed condition, to provide a spring urging the mattress into the declining position whereby release of the catch will automatically bring the mattress into the proper position for shifting the bed frame under the same, and to provide guiding means which make the shift of the bed frame easy and accurate.

Still further objects are to attain these results with simple, reliable and inexpensive means, and to provide a combination of the mentioned nature that can be easily made and assembled, that can be easily converted and that is comfortable in either of its convertible conditions.

Still other objects and advantages will appear from the following description of an exemplifying embodiment of my invention, from the appended claims and from the accompanying drawing in which:

Fig. 1 shows a partly sectional side view of an illustrative embodiment of my invention in sofa condition, the sectionally represented parts being cut along the line 1—1 in Fig. 2.

Fig. 2 shows a top view of the embodiment shown in Fig. 1, upper parts being cut off along the line 2—2 in Fig. 1.

Fig. 3 shows a rear view of a broken off part of the embodiment shown in Fig. 1, a portion of the rear wall being cut off.

Fig. 4 shows a broken off side view of the same embodiment in bed condition.

2

Fig. 5 shows a cross-section taken along the line 5—5 in Fig. 4, the mattress and the cushions being omitted.

Fig. 6 shows a side view of guiding means and of a broken off part of the bed frame in that condition which corresponds to Figs. 1 to 3, but represented on a larger scale.

Fig. 7 shows a cross-section taken along the line 7—7 in Fig. 6 and represented on a still larger scale.

Fig. 8 shows a cross-section taken along the line 8—8 in Fig. 5 and represented on the same scale as Fig. 7.

Fig. 9 shows a side view of a foldable foot of the bed frame, represented on the same scale as Fig. 7.

Referring to the drawings, numeral 3 indicates a frame whic his provided with front feet 4 and rear feet 6 and forms a stationary base. The feet 4 are longer than the feet 6 whereby the frame 3 slopes toward its rear side.

A mattress 9 is positioned over the frame 3. A rear wall 11, two side walls 12 and a front wall 13 form downward extensions of the walls of the mattress 9. A shaft 13 extends near and parallel to the rear wall 11 horizontally and has ends inserted in bores of the side walls 12. The shaft 14 is carried by bearings 15 which are provided with feet 16 affixed on top of the base frame 3 whereby the mattress 9 is rotatably connected to the base frame. In the position shown in Fig. 1, the mattress and its upper surface decline toward the rear side and are about parallel to the frame 3, except that the surface of the mattress may be slightly flared as usual. In this position, the mattress 9 rests on a bed frame which will be described later. When this supporting bed frame is withdrawn, as will be described later, the mattress can swing down about the pivot axis of the shaft 14 into the position shown in Fig. 4 in which the mattress contacts the base frame 3, is immediately suported by the latter frame and in which the front and the rear ends of the mattress are positioned at the same height whereby the upper surface of the mattress is horizontal, except for its slight flare.

One or several springs 17 urge the mattress into the position shown in Fig. 1. For example, the springs 17 may be affixed to the bearings 15 and 50 may pressingly contact the lower surface of the mattress 9. When the supporting bed frame is withdrawn from under the mattress as will be described later, the mattress can be turned by slight hand pressure against the pressure of 55 the springs until the front wall 13 contacts the frame 3 in the position shown in Fig. 4. In the latter position, these contacting parts are temporarily connected, preferably by one or two catches as shown in Fig. 8. This catch may comprise a resilient member 18 affixed to the wall 13 and having a hook shaped end reaching down into and engaging a box 19 inserted in and af-

fixed to the frame 3. The catch can be released by pressure on a member 21.

A bed frame is formed by a rear wall 22, two side walls 23 and a front wall 24 and may be stiffened by a wall 25 extending parallel to the side walls in the middle of the frame. A net of wires and springs, not shown, may extend in well known manner between the walls of the bed frame near its upper surface. The front wall 13 of the mattress is cut out to fit the front wall 24 of the bed frame. The latter wall may extend laterally a little beyond the side walls 23. The bed frame can be shifted through the opening formed by this cut-out like a drawer. In the position shown in Fig. 1, the bed frame is supported by the frame 3, and the wall 24 of the bed frame supports the wall 13 of the mattress whereby the mattress 9 rests on the bed frame and can carry the weight of several persons sitting thereon.

Brackets 26 are affixed to the inner sides of the walls 22 and 24 and are connected by hinges 27 (see Fig. 9) with feet 28. In Fig. 1, these feet are folded into the bed frame and rest on the base frame 3. When the bed frame is shifted into the position in front of the mattress 9 as shown in Fig. 4, the feet 28 drop to the floor and support the bed frame.

In the latter position, the rear wall 22 of the bed frame is adjacent to the front of the front wall 13. The wall 22 is provided with cut out spaces 29 which allow to operate the catch release 21 and to by-pass the catch hook 18 when the bed frame is shifted under the mattress.

The feet 28 support the bed frame in a horizontal position in which its upper surface is considerably lower than the upper surface of the horizontally positioned mattress 9. A layer of cushions 31 having a thickness equal to the difference of these two surface levels is, in the position of Fig. 4, placed on top of the bed frame whereby a double bed of uniform and comfortable height is formed. In Fig. 1, the cushions 31 are placed in the form of several layers vertically over the rear end of the mattress and form the back of the sofa.

The shift of the bed frame between the positions shown in Figs. 1 and 4 is facilitated by guiding means which prevent lateral dislocation of the bed frame during its shift and which may comprise two symmetrically identical devices arranged between the outer sides of the walls 23 of the bed frame and the inner sides of the walls 12 of the mattress. Each of these devices may be constructed as follows:

A rail 32 extending along the inner side of the side wall 12 has lateral projections 33 and 34 which terminate in buttons 35 inserted slidably in substantially vertical slots 36 (see Fig. 2) of a side wall 12 whereby the rail 32 is prevented from shifting horizontally both in longitudinal and in lateral direction, but can adjust its position in vertical direction in a manner allowing the movement described in the following paragraph. Another rail 37 engages the rail 32 slidably whereby these two rails form telescopically extractable elements. Rollers 38 engage the rail 37 rollingly and are rotatably connected to a vertical plate 39 which is affixed to a wall 23 of the bed frame. A stop member 41 may be affixed to the rail 37, for example by a screw bolt 42.

The rollers 38 form a guidance holding the rails 32 and 37 parallel to the longitudinal direction of the bed frame or its side wall 23. Hence, these rails have a rearwardly declining direction when the bed frame is inserted between base

frame and mattress in rearwardly declining direction. But when the bed frame is withdrawn into the front position shown in Fig. 4, the bed frame and the rails extend horizontally or parallel to the floor while the buttons 35 have correspondingly moved vertically in their slots 36.

This device forms a movable connection between the mattress and the bed frame whereby the latter is shiftable between the extreme relative positions shown in Figs. 1 and 2 and in Figs. 4 and 6. The shift results partly from the rolling movement of the rollers 38, partly from the sliding movement of the rail 37. In order to convert the double bed shown in Fig. 4 into a sofa, the feet 28 are folded into the position indicated by dotted lines in Fig. 9, the cushions 31 are taken off the bed frame, and the catch is released whereupon the spring 17 moves the mattress 9 into the rearwardly declining position. In this position, the bed frame fits the front gap between the mattress wall 13 and the frame 3. The bed frame is slightly raised to the level of this gap and is shifted over and along the upper surface of the base frame 3 into the position shown in Fig. 1. This shift is easy because of the declining position of the frame 3 and because of the described guiding means.

I desire it understood that my invention is not confined to the particular embodiment shown and described, the same being merely illustrative, and that my invention may be carried out in other ways within the scope of the appended claims without departing from the spirit of my invention as it is obvious that the particular embodiment shown and described is only one of the many that may be employed to attain the objects of my invention.

If it is desired to convert the sofa into two beds placed apart from each other, the rail 37 may be drawn out until it is completely separated from the rail 32, whereupon the bed frame 23 can be positioned and used independently of mattress 9.

Having described the nature of my invention, what I claim and desire to protect by Letters Patent is:

1. A sofa and double bed combination comprising a base frame, longer front feet and shorter rear feet supporting said base frame in a rearwardly declining position, a mattress positioned over said base frame, a shaft extending horizontally parallel to the rear side of said mattress and rotatably connecting said mattress to said base frame whereby said mattress is turnable between a rearwardly declining position about parallel to said base frame and a horizontal position, said mattress, in said horizontal position resting on said base frame, and, in said declining position, having a vertical distance from said base frame, and a bed frame having a height not larger than said distance, having a width and length smaller than the width and length of said mattress and having a lower surface slidably contacting the upper surface of said base frame whereby said bed frame is shiftable between a position between said base frame and mattress and a position in front of the same, said bed frame, in its first mentioned position supporting said mattress.

2. A sofa and double bed combination comprising a base frame having a rearwardly declining upper surface, a bed frame resting on said base frame in rearwardly declining position, and a mattress pivoted to said base frame near one edge thereof for swinging

movement about a horizontal axis parallel to the rear edge of said mattress, said mattress extending over and being supported by said bed frame in rearwardly declining position and having a front end spaced vertically from said base frame as far as the height of said bed frame, said bed frame having a lower side slidably contacting the upper side of said base frame whereby said bed frame can be shifted into another position in front of said base frame and of said mattress whereupon said mattress can swing about said pivot axis into another position in which said mattress front end contacts said base frame, said mattress having an upper surface extending horizontally in said other position of the mattress.

3. A sofa and double bed combination comprising a base frame; a bed frame supported by said base frame; and a mattress pivoted to said base frame for swinging movement about a horizontal axis parallel to the rear edge of said mattress, extending over and being supported by said bed frame and having a front end spaced vertically from said base frame as far as the height of said bed frame, said bed frame having a lower side slidably contacting the upper side of said base frame whereby said bed frame can be shifted into another position in front of said base frame and of said mattress whereupon said mattress can swing about said pivot axis into another position in which said mattress contacts said base frame, the height of said front end of the mattress over the floor being determined by the combined height of the front ends of said base frame and said mattress, in said other position, being equal to the height of the rear end of said mattress over the floor whereby said mattress has a substantially horizontal upper surface, the height of the front end of the mattress in the first described position being increased by the height of said bed frame whereby the upper surface of said mattress declines rearwardly.

4. A sofa and double bed combination comprising a base frame; a bed frame supported by said base frame; a mattress pivoted to said base frame for swinging movement about a horizontal axis parallel to the rear edge of said mattress, extending over and being supported by said bed frame and having a front end spaced vertically from said base frame as far as the height of said bed frame, said bed frame having a lower side slidably contacting the upper side of said base frame whereby said bed frame can be shifted into another position in front of said base frame and of said mattress whereupon said mattress can swing about said pivot axis into another position in which said mattress contacts said base frame, the height of said front end of the mattress over the floor being determined by the combined height of the front ends of said base frame and said mattress, in said other position, being equal to the height of the rear end of said mattress over the floor whereby said mattress has a substantially horizontal upper surface, the height of the front end of the mattress in the first described position being increased by the height of said bed frame whereby the upper surface of said mattress declines rearwardly; a back removably positioned over the rear end of said mattress when the latter is in said declining position, said back consisting of several layers of cushions of uniform thickness positioned before each other; and feet foldably connected to said bed frame and having a length measured to support said bed frame in said front position at a level of its upper surface lower than the upper

level of said mattress in said horizontal position, the difference of said levels being equal to the thickness of said cushions whereby said cushions can be moved into a position over said bed frame in which they are flush with the mattress in the latter's horizontal position.

5. A sofa and double bed combination comprising a base frame; a bed frame supported by said base frame; a mattress pivoted to said base frame for swinging movement about a horizontal axis parallel to the rear edge of said mattress, extending over and being supported by said bed frame and having a front end spaced vertically from said base frame as far as the height of said bed frame, said bed frame having a lower side slidably contacting the upper side of said base frame whereby said bed frame can be shifted into another position in front of said base frame and of said mattress whereupon said mattress can swing about said pivot axis into another position in which said mattress contacts said base frame, the height of said front end of the mattress over the floor being determined by the combined height of the front ends of said base frame and said mattress, in said other position, being equal to the height of the rear end of said mattress over the floor whereby said mattress has a substantially horizontal upper surface, the height of the front end of the mattress in the first described position being increased by the height of said bed frame whereby the upper surface of said mattress declines rearwardly; a spring urging said mattress to swing away from said base frame; and a releasable catch connecting said mattress and said base frame when said mattress is in said horizontal position.

6. A sofa and double bed combination comprising a base frame; a bed frame supported by said base frame; a mattress pivoted to said base frame for swinging movement about a horizontal axis parallel to the rear edge of said mattress, extending over and being supported by said bed frame and having a front end spaced vertically from said base frame as far as the height of said bed frame, said bed frame having a lower side slidably contacting the upper side of said base frame whereby said bed frame can be shifted into another position in front of said base frame and of said mattress whereupon said mattress can swing about said pivot axis into another position in which said mattress contacts said base frame; a side wall forming a downward extension of said mattress positioned aside of and spaced from a side of said bed frame; rollers positioned laterally of and rotatably connected to said side of said bed frame; and two each other engaging and telescopically extractable rails, one of said rails being rollingly and guidedly engaged by said rollers, the other rail having projections engaging vertical slots in said wall.

HARRY S. VAKASSIAN.
